[57] CLAIM

The ornamental design of a trolling motor housing, as shown
and described.

DESCRIPTION

FIG. 1 is a top perspective view of a trolling motor housing
showing my new design;

FIG. 2 is a right side elevational view;

FIG. 3 is a left side elevational view;

FIG. 4 is a rear elevational view;

FIG. 5 is a front elevational view;

FIG. 6 is a bottom plan view; and,

FIG. 7 is a top plan view.

The broken line showing of a trolling motors associated
elements, shown throughout the drawings, and fluting on the
side of the housing in FIGS. 1, 2, 4, 5, 6 and 7 are for
illustrative purposes only and form no part of the claimed
design. Additionally, the broken lines that run the vertical
length of the housing in FIGS. 1, 2, 3 and 5 and which define
the bounds of the claimed design form no part thereof.
